UNITED STATES PATENT OFFICE

GEORGE W. GRASER, OF SAN JUAN, PUERTO RICO, ASSIGNOR, BY MESNE ASSIGNMENTS,
TO KOPPEL INDUSTRIAL CAR AND EQUIPMENT COMPANY, OF MCKEES ROCKS,
PENNSYLVANIA, A CORPORATION OF PENNSYLVANIA

CANE CAR

Application filed January 9, 1931. Serial No. 507,611.

An object of my invention is to provide a readily operated means for retaining the door holding mechanism of a cane car in door holding position.

Another object of my invention is to provide retaining means which is readily operable into and out of engagement and which when in engagement will automatically resist accidental disengagement.

Referring now to the drawing, Fig. 1 shows in elevation a portion of a cane car embodying my invention; Fig. 2 is an enlarged view showing the locking bar, operating arm and retaining means; Fig. 3 is a side elevation of Fig. 2.

Referring now in detail to the drawing, reference character 1 indicates a cane car having doors 2 pivotally mounted adjacent the upper side of the body and forming the side walls thereof. Adjacent the lower edges of the doors are door holding means, preferably in the form of a lever, mounted in suitable journals 4 secured to the body. This door holding means comprises a bar 5 having offset portions 6 which, upon rotation of the bar, are adapted to move into and out of engagement with the lower edge of the door. On one end of the bar 5 is mounted an operating arm 7, in angular relation thereto, which provides a means of rotating the bar. Mounted on the arm 7 is a link member 8 which is adapted to pass through an opening 9 in one of the upright rigid portions of the body and be engaged by a pivotally mounted member 10 secured to the body. By referring to Figs. 1 and 3 it will be observed that when the link 8 and member 10 are in engagement, the operating arm 7 is retained in position so as to bring the offset portions 6 of the bar 5 into engagement with the lower edge of the door 2, thereby preventing outward movement of the door.

Referring now to Fig. 3 of the drawing it will be observed that the member 10 is pivotally mounted adjacent its upper end on brackets 11 secured to the body and that the horizontal plane of the engagement of the hook portion 12 of the member 10 with the link 8 is below a similar plane of the pin 13 securing the member 10 to the brackets. In

this manner the link 8 secured to the operating arm 7, being held in tension by the arm 7 and doors 2, tends to cause the rotation of the member 10 in a direction towards the link member, thereby preventing accidental separation of the link and hook. For convenience in operating the member 10, a handle 14 is formed on the member below the point of mounting to the brackets 11 and this handle assists, by the force of gravity, in holding the members 8 and 10 in engagement.

Assuming the side doors of the body to have been opened to discharge the lading, the operation of locking the doors in closed position is as follows: the operator, after closing the doors, grasps the operating arm 7, moving it upwardly towards the car body into the position shown in Fig. 1 after which the link 8 is inserted through the opening 9 in the car body and the member 10 is manipulated so as to cause the hook portion 12 to engage with the link member 8. The link 8 and hook 12 will now automatically remain in engagement with each other as previously explained. To release the operating arm, the operator grasps the handle 14 of the member 10, moving it in the direction of the arrow of Fig. 3, so as to rotate the hook portion of the member 10 downward and out of engagement with the link 8 after which the operating arm 7 can be rotated outwardly and downwardly to release the doors for opening.

Should the operating arm 7 become distorted during operation of the car, the mechanism will still be operable since the arm 7 is of sufficient length to be sprung towards the car body and the link 8 can be rotated into position to enter the slot 9 of the body.

From the above it is apparent that I have provided a locking means comprising a small number of parts which are readily engageable with each other and that the one movement of the handle 14 of the member 10 releases the operating arm to permit the door holding means to be moved free of the car doors.

Having thus described the invention what I claim as new and desire to secure by Letters Patent is:

1. In a cane car having an outwardly swinging door, a lever journaled to the body

- adjacent the free edge of said door, offset portions on said lever for engaging with the door to hold the door in closed position, and locking means for maintaining the lever in door-holding position, said means comprising a link mounted on said lever, a link engaging hook member mounted on the body and manually operable to engage with said link when the lever is moved to door-holding position.
2. In a cane car having an outwardly swinging door, a lever journaled to the body adjacent the free edge of said door, offset portions on said lever for engaging with the door to hold the door in closed position, and locking means for maintaining the lever in door holding position, said means comprising readily engageable mutually supporting members pivotally mounted on the body and on said lever.
3. The combination in a cane car having upright side members, of doors pivotally mounted at the sides of the car, a bar mounted in journals at the sides of the car and having offset portions for holding the doors in closed position, an operating member for said bar and locking means for said operating member, said means comprising a link pivotally mounted on said operating member and a link engaging hook on said car body.
4. In a cane car having an outwardly swinging door, a door holding means journaled on the car adjacent the free end of said door and movable into engagement with the door, an angularly disposed operating arm on said door holding means, a link on said operating arm and a link engaging member pivoted to the car, any door releasing movement of the operating arm, while the said link and member are in engagement, tending to rotate said member in a link engaging direction.
5. In a cane car, in combination, an outwardly swinging side door pivoted to the car body, suitable door holding means journaled to said body, an operating arm for said means and pivotally mounted members on said operating arm and body for retaining the door holding means in position, said members when in engagement mutually supporting each other against accidental separation.
6. In a cane car in combination, an outwardly swinging side door pivoted to the car body, suitable door holding means journaled to said body, an operating arm for said means, a bifurcated member pivotally mounted on said arm, a member pivotally mounted on said body for engaging said bifurcated member, said members when in engagement maintaining said operating arm in door locking position.
7. In a cane car having an outwardly swinging door in combination, a door holding means journaled at the car adjacent the free end of said door and movable into engagement with the door, an angularly dis-

posed operating arm on said door holding means, a pivotally mounted latch on said body, a tension member between said pivotally mounted latch and operating arm, said latch releasably engaging said tension member.

8. In a cane car in combination, an outwardly swinging side door pivoted to the car body, suitable door holding means journaled to said body, an operating arm for said means and pivotally mounted members on said operating arm and body for maintaining said operating arm in door locking position, said body mounted member having a cam shaped surface adapted to be engaged by said operating arm member and supported thereby.

9. In a cane car in combination, an outwardly swinging side door, door holding means journaled on the car adjacent the free end of said door and movable into engagement with the door, an angularly disposed operating arm on said door holding means, a bifurcated member pivotally mounted on said arm, a member pivotally mounted on said body adapted to engage said arm member within said bifurcations.

10. In a cane car having an outwardly swinging door, door holding means journaled on the car adjacent the free end of said door and movable into engagement with the door, suitable door holding means journaled to said body, an operating arm for said means, a bifurcated member pivotally mounted on said arm, a downward depending member pivotally mounted on said body having a portion thereof adapted to engage said bifurcated member and support same in engagement therewith.

GEORGE W. GRASER.
